UNITED STATES PATENT OFFICE.

BYERS W. KADEL, OF BALTIMORE, MARYLAND, ASSIGNOR TO THE T. H. SYMINGTON COMPANY, OF NEW YORK, N. Y., A CORPORATION OF DELAWARE.

DRAFT RIGGING.

1,426,991.

Specification of Letters Patent. Patented Aug. 22, 1922.

Application filed August 26, 1921. Serial No. 495,635.

To all whom it may concern:

Be it known that I, BYERS W. KADEL, a citizen of the United States, residing at Baltimore, in the State of Maryland, have invented certain new and useful Improvements in Draft Rigging; and I do hereby declare the following to be a full, clear, and exact description of the invention, such as will enable others skilled in the art to which it appertains to make and use the same.

The invention relates to draft rigging for railway cars, and more particularly to improvements in striking members adapted for use with modern railway equipment.

The principal object of my invention, generally considered, is to provide in combination with cheek plates or stop lugs a striking member having a high degree of elasticity, such striking member being intimately associated with the stop lugs to provide for the transmission of blows from the coupler to the center sills of the car without detriment to the latter and without injury to the end sill.

Another object of my invention is to provide cheek plates or draft lugs having shoulders to support and additional shoulders to resist blows impressed upon the striking member carried by the said stop lugs or cheek plates.

A still further object of the invention is to provide stop lugs or cheek plates having associated therewith a striking member, the said striking member being readily detachable and replaceable without cutting rivets or otherwise dismantling the car construction.

To these and other ends the invention comprises the various elements and combinations of elements as hereinafter set forth, the novel features whereof are pointed out in the claims.

In the drawings,—

Figure 1 is a partial longitudinal section of a car underframe illustrating my invention, some of the elements being shown in side elevation.

Figure 2 is a transverse horizontal section of the construction shown in Fig. 1, certain of the parts being illustrated in plan.

Figure 3 is an end view, and Figure 4 a fragmentary view of a portion of one of the cheek plates or stop lugs.

The numeral 1 designates the center or draft sills of a railway car, 2, 2 the forward

ends of a horizontal yoke, 2^a the forward end of a conventional form of cushioning mechanism, the latter being illustrated in dotted lines, and 3 a front follower.

Connected to the vertical faces of the sills 1 and preferably also connected to the top cover plate 4 are spaced stop lugs or check plates 5. Since these cheek plates are identical it will only be necessary for a complete understanding of the invention to describe one of them in detail. The cheek plate 5 is provided with a vertically extending web 6 which abuts the adjacent face of the sill 1. At its inner end there is provided an outwardly extending flange 7 which forms the follower engaging face of the cheek plate. This flange 7 is interrupted as at 8 to provide space for the reception of the adjacent yoke arm 2. It will be observed, however, from Fig. 2 that the flange 7, even at the points adjacent the opening 8, projects inwardly from the web 6 to provide a guiding member for the yoke 2. As clearly shown in Fig. 2, the cheek plate 5 is provided in rear of the follower engaging flange 7 with a rearwardly extending web 9, the said rearwardly extending web being adapted to reinforce and strengthen the rearward end of the slot 10 with which the cheek plate is provided. Projecting inwardly from the web 6 and preferably extending longitudinally of the plate 5 are a plurality of horizontal flanges 11, 12, 13 and 14. The flanges 13 and 14 extend the full length of the cheek plate and are connected at their forward ends by a vertical flange or web 15 which provides means for the connection of the coupler carry iron 16. The flanges 11 and 12 terminate short of the end of the plate and are connected at their forward ends by a vertical web or flange 17, and extending forwardly from a point adjacent the intersection of the webs 12 and 17 is a further horizontal inwardly extending flange 18. The coupler key slot 10 is preferably provided with a marginal flange 19, and the vertical edges of the flange 7 are also reinforced by vertically extending webs 20.

The coupler 21 is operatively connected to the yoke 2 by means of the transversely extending coupler key 22 in the well known manner. The vertical flanges 17 of each cheek plate are perforated as at 23 to receive a fastening bolt 24, the said bolts being adapted to extend through a wooden

striking block 25 and through a metallic face plate 26 which overlies the forward face of the striking block.

The striking block 25 is seated at either 5 end on the flanges 18 of each cheek plate and is in direct bearing contact with the vertical flanges 17. It will thus be seen that blows delivered to the striking block from the coupler horn 27 will be transmitted to the shou- 10 ders or flanges 17 and be carried to the sills 1 through the medium of the rivets 28 which connect the cheek plates to the car sills and to the top cover plate. It is to be observed that the vertically extending rivets 28 at the 15 upper and lower portions of the cheek plates extend through the flanges 29 of the center sills affording thereby an additional connection for the said cheek plates.

It might be here pointed out that by utilizing 20 a wooden striking block I am enabled to cushion the blows delivered by the coupler horn to a very appreciable extent, and at the same time by providing a cushion for the striking horn I also furnish a replaceable 25 striking member which, in case of damage, may be readily removed by simply unscrewing the nuts 30 from the ends of the bolts 24.

In the particular embodiment of the invention here shown it will be observed that the 30 upper flanges of the center sills overlie the striking member and thus in connection with the flanges 17 and 18 form an outwardly open pocket for the reception of this striking member. The end sill 31 is also connected to 35 the cheek plates 5 by means of some of the

rivets 28, and is in turn connected to the end framing 32 by means of the rivets 33. The bracing members 34 which extend laterally from the outer faces of the center sills are also tied to the said sills by means of the 40 horizontally extending rivets 28.

I claim:—

1. In a draft rigging, the combination 45 with the center sills of a car, of cheek plates connected to the end portions thereof, said cheek plates each being provided with a recess formed by intersecting flanges, and a wooden striking block having its end portions positioned in said recess.

2. In a draft rigging, the combination 50 with the center sills of a car, of cheek plates connected to the adjacent faces thereof, said cheek plates each being provided with a seat and a wooden striking block extending between said cheek plates and seating thereon, 55 and means for maintaining said block in position.

3. In a draft rigging, the combination 60 with the center sills of a car, of cheek plates connected to the adjacent faces of said sills, 65 each cheek plate having a plurality of inwardly extending upright flanges thereon, a follower adapted to bear against one of said flanges on each plate, and a striking block adapted to bear against the other flange of each plate, and means extending between said flanges on each plate for reinforcing the same.

In testimony whereof I affix my signature.
BYERS W. KADEL.
